UNITED STATES PATENT OFFICE

JOHN C. OLSEN, OF BRONX, NEW YORK

DRAPERY

Application filed January 15, 1930. Serial No. 420,951.

This invention relates to improvements in draperies.

The principal object of the invention resides in a drapery which is cut and hemmed so that when in a supported position upon a curtain rod, the same may be adjusted thereon to produce varied artistic effects, depending upon the space to be spanned by the drape and the nature of the artistic furnishing of the room so as to be in keeping therewith.

Another object is to provide a drapery of segmental shape in plan having four sides, three of which are hemmed to facilitate the insertion of a curtain or drapery rod there-through so that when the drapery is in a hung condition the same may be gathered upon the rod to produce an attractive and pleasing decorative effect.

Other objects will appear as the specification is proceeded with, and in which:

Figure 1 is a plan view of the rear side of the drapery in a stretched or flat condition.

Figure 2 is a front elevational view showing the drapery in its supported position upon a rod, and illustrating one artistic effect produced thereby.

Figure 3 is a view similar to Figure 2, but showing the drapery in an adjusted position to produce a different artistic effect.

Figure 4 is a detail sectional perspective view through one of the hemmed edges of the drapery.

Referring to the drawing by reference characters, the numeral 10 designates my improved drapery in its entirety and which includes a flexible fabric body 11 constructed of a single piece of material and cut to provide identical side edges 12-12, a straight top edge 13 and an outwardly curved bottom edge 14, the latter being covered with a braid 15 from which tassels 16 depend. The material from which the body 11 is constructed may vary depending upon the particular kind and design desired, while the side edges 12-12 and the top edge 13 is folded inwardly and stitched as at 17 to provide hems 18, the meeting hems between the top straight edge 13 and the curved side edges 12-12 being slit as at 19 to prevent any bulging of the material when the drapery is suspended

in a hung position from a drapery or curtain rod 20 as shown in Figures 2 to 4, inclusive.

By inserting the curtain rod 20 through the hem 18 around the sides 12-12, and top edge 13, the ends of the curved bottom edge 14 are lifted upwardly to a point adjacent the rod as shown in Figures 2 and 3, which causes the fabric body to assume a decorative position and by adjusting the width of the drapery upon the rod, various artistic effects may be produced, such as for instance as shown in Figure 2 where the drapery is gathered sufficiently to produce hanging folds or rolls, the lower bottom edge being semi-circular, while in Figure 3 where the drapery spans a shorter width, the gathering is increased, thus causing the drapery to assume a shield shape and in which the rolls or folds are closer together and of an increased number than those shown in Figure 2.

Although I have shown two adjustments of the drapery upon the rod, it will be appreciated that various other decorative and artistic effects may be produced by an interior decorator or one skilled in the art by arranging the gathered portion accordingly.

From the foregoing description, it will be understood that by cutting the drapery into the shape shown, and hemming three sides of the same, various effects may be produced with a single drapery, thus eliminating the practice of cutting the draperies in various shapes to produce the varied effects desired.

Having thus described my invention, what I claim as new and desire to secure by Letters Patent is:—

1. A drapery comprising a piece of material having four sides, all but one side being hemmed to facilitate the passage of a curtain rod on which the material may be hung and gathered to produce varied artistic effects.

2. A drapery comprising a piece of fabric material having an outwardly curved bottom edge, identical side edges, and a short straight top edge, hems extending around said top edge and said side edges and adapted to accommodate the passage of a curtain rod

on which said piece of fabric material is gathered to produce varied artistic effects depending upon the width of the space over which the material is to be draped.

- 5   3. A drapery comprising a piece of fabric material having an outwardly curved bottom edge, identical side edges, and a short straight top edge, tassels depending from said bottom edge, hems extending around said top edge and said side edges and adapted to accommodate the passage of a curtain rod on which said piece of fabric material is gathered to produce varied artistic effects depending upon the width of the space over which the material is to be draped.

15   In testimony whereof I affix my signature.
JOHN C. OLSEN.
